OF BOSTON, MASSACHUSETTS, A CORPORATION OF MASSACHUSETTS

ART OF DESICCATING LIQUIDS

Application filed June 9, 1925. Serial No. 35,884.

The present invention relates to drying liquid and semi-liquid products and more particularly to drying liquid products delivered to the drying air in the form of a spray. 5 Various expedients have been suggested for drying liquids, such as milk, liquid soap, etc., sprayed into drying air for the purpose of removing the water and collecting the remaining solid substance in the form of a merchantable product. Difficulty has been experienced, however, in removing the water from the liquid product and thereafter separating the product from the air without injury either to the product or without employing a 10 complicated or elaborate apparatus. 15

One object of the present invention is to provide a relatively simple and compact apparatus for drying liquid products and recovering the dry residue in a single operation 20 and without injury to the product.

With this and other objects in view, one feature of the present invention contemplates delivering the liquid to be dried into a stream of drying air from the lip or edge of a rotating nozzle in such a manner that the liquid is 25 intimately associated with the drying air without substantial contact with the walls of the container.

A further feature of the invention contemplates means for maintaining the drying air and entrained liquid in continuous motion throughout the drying chamber and thereafter permitting a substantially free passage 30 of air with entrained liquid from the chamber while forcibly separating the dried residue due therefrom.

Still further features of the invention consist in certain novel features of construction, combinations and arrangements of parts 40 hereinafter described and claimed, the advantages of which will be obvious to those skilled in the art from the following description.

In the accompanying drawings illustrating the preferred form of the invention in its apparatus aspect, Fig. 1 represents a longitudinal section in elevation of the drying apparatus embodying the features of the invention; Fig. 2 is a detail illustrating a 45 partial front elevation of the apparatus; Fig. 3

is a detail illustrating a side elevation partly in section of the means for spraying liquid into the drying air and for delivering air to the chamber; and Fig. 4 is a detail showing the air seal for the separator. 55

In the embodiment of the invention illustrated in the drawings a substantially cylindrical drying chamber 10 is provided with means at one end for delivering liquid and drying air thereto and at the opposite end for separating the dried residue from the air. The cylindrical drying chamber may have a length approximating three or more times the diameter. The liquid substance to be dried is delivered into one end of the chamber at approximately the axis in the form of a funnel shaped spray which immediately encounters the drying air. The direction of the liquid in the air is such that the liquid is caused to intimately associate with the air without impinging on the adjacent walls of the container or becoming immediately subjected to an excessive volume of hot dry air, which would cause the immediate formation of a dry residue on the walls of the container adjacent the delivery point of the liquid. In actual practice, the drying of the liquid is progressive and uniform as it traverses the length of the drying chamber and is substantially wholly completed when 60 the air and entrained substances reach the opposite end of the chamber and encounter the means for separating and recovering the dry residue. 65

As indicated more particularly in Figs. 1 and 3, a nozzle 20 projects inwardly from an end wall 22 of the container. This nozzle is detachably connected by screws 24 with a hollow supporting head 26 mounted in the wall 22 as indicated. Journaled within the nozzle and projecting slightly beyond the inner edge of the nozzle is a rotary atomizing cup 28 supported upon the end of a tubular shaft 30 which is journaled at its opposite end in anti-friction bearings 32 and 34, both of which are supported within the projecting portion 36 of the supporting head 26. The atomizing cup is rotated at a relatively high rate of speed by a grooved pulley 38 mounted on the outer end of the shaft 30 and partially 70

enclosed by an end casting 40. The cup is rotated through the pulley in any convenient manner as by an electric motor, not shown, which may be connected to the pulley through a belt. Supported concentrically within the rotating cup is a feed tube 42 having an inner down turned delivery end 44, which feeds the liquid on to the bottom of the cup back of the outer delivery edge. This feed tube is supported within the end casting 40 and is adjustably secured in place by a thumb screw 46 which permits the position of the delivery end to be varied with respect to the interior of the cup. The feed tube is connected with a liquid storage tank 50 through a connecting pipe 52 and valve 54. The storage tank contains the liquid to be dried, the flow of which may be regulated through the valve 54. Surrounding the rotary cup within the head 26 and nozzle 20 is an annular air chamber 56 which is connected through a pipe 58 with a source of air pressure, such as a blower 60. This serves to deliver atmospheric air at the necessary pressure and velocity about the outer edge of the rotating cup 28. As the liquid is delivered onto the interior surface of the cup from the end 44, it works outwardly and thereafter is spun from the outer edge 62 in a fine stream. The atomized liquid is immediately engaged by air emerging from the nozzle about the cup, which diverts the spray of liquid and causes it to flow outwardly in a generally funnel shaped stream. In addition to the air supplied about the rotary cup 28, air in materially larger volume is supplied about the nozzle through a duct 70, as indicated more particularly in Figs. 2 and 3. This air passes through a heater indicated at 72 and has capacity for absorption of a comparatively large quantity of liquid. Operating in conjunction with the two sources of air supply previously mentioned is a third current of air supplied to the conical end wall 76 through an air duct 78 which enters the conical end wall from the outside nearly tangentially, the elongate orifice therein, shown in dotted lines, at 78^a coinciding with the similarly shaped terminus of said duct 78. This air duct, as indicated in Figs. 1 and 2, is designed to supply air tangentially to the container, the combination of the two air currents serving to cause a spiraling movement of the entire body of air with entrained liquid in a direction lengthwise of the container. The air duct 78 is also connected with the heater 72, which serves to supply heated drying air delivered through both the ducts 78 and 70. The control of the drying air in this manner serves to remove moisture from the liquid substance and maintain the substance to be dried out of contact with the walls of the container until substantially all of the liquid has been exposed by the air. This prevents incrust-

ing the walls of the container by partially dried substances and permits the recovery of substantially all of the dried residue. Any small percentage of the dried residue which contacts and remains on the inner wall of the container may be readily removed therefrom in its dry, granular or powdered state. After its traverse throughout the length of the container, the air with the dry residue carried thereby encounters a rapidly revolving separator 90, which comprises a tubular screen basket having a mesh suited to the degree of fineness of the dried residue. The exit of the drying chamber is completely closed except through the screen 90 and all of the drying air is compelled to pass therethrough. This separator screen, as indicated more particularly in Fig. 1, consists of a slightly conical member closed at the inner end 92 and mounted upon a shaft 94 which is journaled at its opposite ends in bearings 96 and 98. The inner bearing 96 is supported in a skeleton spider 100 mounted within the container in such a manner as not to interfere with the flow of air therethrough and the outer bearing is mounted in a similar spider 102 enclosed in a discharge passage 104. The basket is revolved at high speed from a pulley 106 supported outside of the casing 104 and driven in any suitable manner. The casing 104 communicates with a discharge duct 108 connected with a blower of ample capacity to maintain the desired flow of air through the container. The dried residue either through direct contact with the surface of the rapidly revolving screen or through centrifugal action initiated by the screen is discharged from the air and collects in major portion in a receiving pocket 110 formed in the lower portion of the cylindrical container beneath the separator member.

It is very important that leakage of air laden with solid material between the revolving separator and the edge of the casing shall be effectually prevented. This is accomplished in the present invention in a unique and practical manner by providing for a counter-current of air between the outer edge of the separator and the adjacent wall of the casing. To this end, as shown more particularly in Figs. 1 and 4, the outer edge of the screen basket is supported on a ring 120 having an outwardly extending flange 122 which is substantially parallel to and adjacent to the stationary flange 124 forming a part of the casing. The flange 122 is provided with blades 126 preferably cast thereon and adapted to insure a current of air in the direction of the arrow in Fig. 1. With this construction, the rotation of the separator causes the blade 126 to act as a fan and introduce clean air from beyond the separator back into the main drying chamber. This countercurrent of air is sufficient to effectual-

ly prevent leakage of dust laden air from the drying chamber into the exhaust passage and dispenses with the necessity of packing joints and similar devices for closing the openings.

5 If desired, in order to conserve heat, the exterior of the cylindrical drying chamber may be covered by a layer of heat insulating material 112, such as asbestos packing or similar material.

10 The present invention provides an efficient and self-contained apparatus for effectually drying and recovering materials originally in a liquid form. In actual practice, the drying chamber enclosed by the casing has a 15 diameter approximating six feet and a length of sixteen feet and is employed for drying liquid hemoglobin and liquid blood serum. The apparatus as employed for this purpose effectually dries and recovers the serum and 20 hemoglobin in a granular merchantable form without oxidizing or causing incrusting on the walls of the container or moving parts. By utilizing the current of relatively cool air about the atomizing cup, the latter is 25 maintained cool and incrustation upon the walls of the cup prevented. In drying certain other liquid products, it may be possible to dispense with the current of relatively cool air about the cup and heat the air for 30 this purpose.

Although the apparatus as illustrated and described is particularly designed for the spray drying of products originally in a liquid form, it will be nevertheless obvious 35 that the apparatus could be employed, if so desired, for cleaning or washing dirty air by spraying into the dirty air washing liquid which would moisten and agglomerate the solid particles and permit them to be separated.

40 The character of the liquid spray delivered from the front edge 62 of the atomizing cup may be varied by altering the position of the delivery end 44 of the feed tube 42 lengthwise 45 of the interior of the cup. By suitably adjusting the position of the feed tube, the spray may be governed to cause a thorough intermingling with the drying air and yet not penetrate the surrounding envelope of air in 50 a manner to engage with and form incrustation on the wall of the container. The control of the liquid spray in this manner is an important and desirable adjunct of this class of apparatus.

55 It will be evident to those skilled in the art that with this form of apparatus the drying of the liquid product is uniform and continuous throughout the length of the drying chamber. This is due in part to the fact that 60 the liquid spray, as delivered, encounters the entering main stream of drying air when said drying air is hottest, and is thereafter directed concurrently with the direction of air flow, being removed from objectionable contact with the walls of the drying chamber

through the surrounding envelope of heated air delivered tangentially to the inner wall of the chamber and spiraling thereabout in a lengthwise direction. Furthermore, the employment of a substantially horizontal drying chamber with the product supported therein during its traverse lengthwise of the chamber, precludes the precipitation of a part of the dried material to the bottom of the drying chamber as frequently happens 70 with a vertical chamber in which the movement of the product during the drying period is downward and concurrent with the flow of drying air. In drying liquid solutions such as blood, milk or liquid soap, the use of the 75 heated drying air inevitably produces dried hollow particles or granules which may be accompanied by a certain degree of swelling or enlargement of the dried particles or granules, probably due to the initial and superficial 80 drying of the liquid drops with a subsequent expansion and evaporation of moisture from the interior, these materials having a composition such as to resist complete fracture of the granules into a powdered form during 85 the progress of the drying action. The resulting product is characterized by an interior void or voids, may be described as granular rather than powdered, and due to a comparatively large superficial area is more 90 readily soluble than would be a product not so constituted. Obviously such a product, if not subsequently powdered or ground into a powdered state, bulks larger than a finely- 95 divided powder.

100 I claim:

1. The process of producing a dried product from liquid solutions of materials such as blood, milk or soap, in an enclosed treating space, which comprises the preparation 105 of the material in the form of liquid stock, forcibly centrifugally spinning the liquid stock radially in all directions from a central and generally horizontal axis, projecting an annular current of gas about and in proximity to the delivery region of the spray, the current of gas having a direction and velocity such that it intercepts and diverts the spray and continues therebeyond in a generally axial direction, supplying a further volume of 110 drying gas annularly about the central axis and the first mentioned current and projected generally in an axial direction such that the two currents of gas with the combined spray continue with a like manner of flow, which persists in a well defined axially-moving column entraining the gas-borne spray in process of drying, supplying a further current of gas in proximity and tangentially to the 115 wall of the treating space in a manner to contact with said first named currents to entrain and propel spirally and axially spray particles in process of drying which may tend through gravity to drop from the axially-moving current of drying gas before drying is 120 125 130

completed, and subsequently separating dried particles from the gas.

2. Apparatus for producing a dried product from liquid solutions of materials such as blood, milk or soap, comprising an enclosed drying chamber, a rotary cup spray member at one end of the chamber for spinning liquid stock centrifugally and radially from a central and generally horizontal axis, means for projecting an annular current of drying gas about the spray member with sufficient velocity to move it axially throughout the length of the chamber in a well defined and persisting stream, means intermediate the rotary spray member and first mentioned projecting means for directing upon and intercepting the spray with an annular gas current moving in like manner of flow with the first mentioned current and diverting the spray into a generally axial direction for causing the combined gas currents and entrained spray to be propelled axially throughout the chamber in a well defined stream which maintains the spray gas borne until completion of drying, and means for thereafter separating the dried particles from the drying gas.

3. Apparatus for producing a dried product from liquid solutions of materials such as blood, milk or soap, comprising an enclosed drying chamber, a rotary cup spray member at one end of the chamber for spinning liquid stock centrifugally and radially from a central and generally horizontal axis, means for projecting an annular current of drying gas about the spray member with sufficient velocity to move it axially throughout the length of the chamber in a well defined and persisting stream, means intermediate the rotary spray member and first mentioned projecting means for directing upon and intercepting the spray with an annular gas current moving in like manner of flow with the first mentioned current and diverting the spray into a generally axial direction for causing the combined gas currents and entrained spray to be propelled axially throughout the chamber in a well defined stream which maintains the spray gas borne until completion of drying, means for tangentially introducing a stream of gas at the spray end of the chamber adjacent the wall thereof and outside said annular current projecting means, and means for thereafter separating the dried particles from the drying gas.

In testimony whereof I have signed my name to this specification.

FRED FORREST PEASE.
